GAS BURNER

Philip S. Harper, Chicago, Ill.

Application December 26, 1933, Serial No. 703,902

6 Claims. (Cl. 158—117)

This invention relates to burners, and particularly to gas range burners of the round or ring style, and this invention may either be used with a single burner or double section type of burner where a simmer section is combined in a single unit with a large section burner. This invention also applies to a burner having a separable burner center wherein or adjacent to which the burner ports are formed.

10 In such burners the separable center is frequently made of die cast aluminum in order to manufacture such a part in a practical manner, and some provision must be made for keeping such a center below its melting point. The hottest 15 portion of such a burner is at the burner ports at the outer rim of such a center, and in previous burners this portion has been cooled by contact of this rim or by contact of teeth formed on this rim with the lower and cooler part of the burner. Such contact is uncertain both on account of slight irregularities in the mating parts and because in actual practice such burner center may not be tightly forced or screwed into place; consequently I have devised other more 20 reliable means of cooling in this invention. Such 25 method consists in the positioning and form of the teeth forming the burner ports whereby a large area is exposed to the cooling action of the gas flowing inside of the burner when the burner is in operation. Experiment proves that there 30 may be greater cooling of the burner center in the present invention than in past forms where teeth in the burner center have contact with the lower member of the burner, even though there 35 may be no contact of the rim of the burner center in the present invention with any other part of the burner.

Heretofore burners of the round corrugated port type have been made and used but in all 40 practical forms which have come in general use it has been necessary to use a very small diameter of burner with a wide spreading flame when the burner is turned on full but with a very disadvantageous concentration of heat at a low 45 burning flame. In these burners previously used, it has not been possible to devise a large burner having a proper wide distribution of heat at a low frying flame, at the same time a burner having central ports so as to avoid a cold central portion, 50 at the same time a burner having the upper roof of the ports slanting at 45° or more to the vertical so as to be unlikely to clog from spillage, and at the same time a burner of this type in which the central ports when ignited will in turn ignite 55 the ports of the outer section. This advantageous

result has been accomplished in the present invention by the arrangement of the ports as hereinafter disclosed. Also in all previous burners of the ring corrugated port type and of the most efficient and even heating style having burner ports towards the center of the burner as well as on the outer ring, it has been necessary to use drilled burner ports opening at least partially on a horizontal plane and consequently liable to become clogged or filled with spillings or boilovers 10 on the burners. This has also been overcome in one form of the herein-described invention.

It has not been considered possible on previous burners of the corrugated port style to provide a burner of the double section type having in the 15 unit a simmer section which may be burned independently of the remainder of the burner. It is by the form, shape and arrangement of parts that I have devised the burner of this invention in which this may be accomplished, and as well 20 I have devised a burner to overcome objections as set forth in previous burners of this general type.

The object of this invention is to provide a 25 large burner having only a moderate spread of flame at full flame and consequently a burner in which there is a high efficiency and at the same time a burner which when having a reduced flame for frying, provides a wide spread of uniform heat.

Another object of this invention is to provide a 30 burner of the type indicated in which there are central burner ports as well as an outer ring of ports thereby providing a burner of higher efficiency as well as a burner which eliminates a 35 cold spot in the center of the flame.

Another object of this invention is to provide a 40 burner of the corrugated port type in which the port area may be changed by the raising or lowering of the interior portion of the burner head.

Another object of this invention is to provide a 45 round burner of the corrugated port type having ports in the center as well as in the outer ring in which all of the burner ports open on a vertical plane so that none of the ports are liable to closure from spillage.

Another object of this invention is a round 50 burner of the corrugated port type having two sections, a large section and a simmer section, where the simmer section is entirely separated from the outer section and consequently may be 55 separately burned.

Another object of this invention is the provision of the double section burner having a practical means of enclosing each section as well as 55

of separating each section from the other section.

Another object of this invention is to provide a double section round burner of the corrugated port type having a burner head portion separable from the mixing tube portion whereby this burner head portion may be made of different material more readily adapted thereto than the material commonly used and necessary for the mixing tube portion of the burner.

These and other objects of this invention will be more apparent from the following description and from the drawing in which:

Figure 1 is a plan view of a burner made in accordance with this invention;

Figure 2 is a sectional elevation along the line 2—2 of Figure 1;

Figure 3 is a sectional plan along the line 3—3 of Figure 2; and

Figure 4 is a sectional view in elevation along the line 4—4 of Figure 1.

Referring now to the drawing, in which like figures refer to like parts throughout the drawing, and to Figure 1 particularly, a burner is shown having a mixing tube portion 10 which in this form of this invention is a cored iron casting having therein a small mixing tube 11 and a large mixing tube 12, said mixing tubes running parallel and being separated at all points by a wall 13. The entrances to these mixing tubes have two holes 14 and 15 adapted for the usual double gas cock commonly known and in use, and which consequently is not shown or described in this specification. Said nozzle hole 14 is substantially in axial line with said mixing tube 12 and said nozzle hole 15 is substantially axial line with said smaller mixing tube 11. The entrance end of said mixing tubes casting 10 has air entrance holes 16 and 17, shown by dotted lines, and said opening 16 allows admission of air in mixing tube 12 while said opening 17 allows admission of air to aforesaid mixing tube 11. At the opposite end of said mixing tube from said air openings 16 and 17, said mixing tubes diverge from one another, curving in circular fashion, but the large mixing tube curves on a wider radius at 18 while the smaller mixing tube curves on a smaller radius at 19 for purposes herein-after described. The curved portions of said mixing tubes extend upward into a flat surface 20 in which surface both of said mixing portions 18 and 19 open for the greater part of their curving length.

Bolts 21 and 22 are provided which pass through corresponding holes 23 and 24 in said mixing tube casting and project from the top of aforesaid flat surface 20. The projecting portion of said bolts 21 and 22 are tapped into a burner head 25 at points 26 and 27.

Said burner head 25 has a small circular chamber 28 and a large circular chamber 29. Said small burner chamber 28 is formed immediately above the curving section 19 of the small mixing tube 11 and said large burner chamber 29 is formed immediately above the curving portion 18 of the larger mixing tube 12. This burner head 25 has a flat seating portion corresponding in diameter both external and internal to the flat portion 20 of the mixing tube casting having the curving portions 18 and 19. Said small burner chamber 28 has an opening along part of this circumference at least partially registering with the opening in the surface 20 of the curving portion 19 of the small mixing tube 11 and the large burner chamber 29 has an opening partially 75 around its circumference substantially register-

ing with the opening into the seating surface 28 of the curving portion 18 of the larger mixing tube 12. A gasket may be desirably used in said seating surface having suitable holes therein so as to allow free passage of gas from the mixing tubes 5 in the mixing tube casting 10 into the corresponding chambers in the burner head 25.

This burner head 25 comprises an outer cylinder 31 and an intermediate cylinder 32 and an inner cylinder 33, all of said cylinders being connected by an end wall 34 which is in contact throughout the greater portion of its extent with the seating surface 28 on the mixing tube casting 10.

The aforesaid intermediate wall 32 has a thread 15 35 tapped therein and into this thread there is screwed a burner center 36 having an externally threaded extension 37 with a thread thereon suited to engage the aforesaid thread 35 in the burner head 25. Said burner head center has an inner cylindrical surface 38 into which said inner cylinder 33 of the burner head 25 extends with a free but close fit whereby only immaterial gas leakage can take place between said parts. Said inner cylindrical surface 38 of the burner head 25 20 has formed therein a plurality of diagonal slots 39 opening in this cylindrical surface 38 and as well in the under side 40 of this burner head center. It can be seen that this under side 40 of said burner head center 36 forms the upper 25 wall and closes the smaller annular chamber 28 in the burner head 25.

Referring further to the burner head center 36 it can be seen that this part is in the form of a cone and as it extends upward its diameter 35 increases. The outer diameter of said burner head center 36 is substantially in the form of a cylinder 41 and its cylindrical surface fits freely but closely within the outer cylinder 31 of the burner head 25. These cylindrical surfaces do 40 not engage as there is an appreciable clearance between the two parts through which gas flows and consequently this clearance forms part of the port area of the burner. The outer cylindrical portion 41 in the burner head center 36 has 45 a plurality of burner port slots 42 therein which extend inward and downward and through the under surface 43 of the outer portion of said burner head center 36. Said under surface 43 extends between the outer wall 31 and the intermediate wall 32 of the burner head 25 and it thereby forms the upper closure of the larger chamber 28 of the burner head 25.

Referring now to the Figures 2 and 4 of the drawing, it can be seen that the burner head center 36 has a projecting seating ring 44 over the upper end of the intermediate wall 32 in the burner head 25. This seating ring 44 limits the extent to which the burner head center 36 may be screwed onto the threads and so limits the minimum opening of the slotted burner ports 39 in the center of the burner and as well the minimum opening of the slotted burner ports 42 in the outer diameter of the burner as will be apparent from the drawing. This projection 44 forms a 55 perfectly tight seat against leakage of gas when it is bearing against the upper end of the intermediate wall 32. It can be seen from this description and from the drawing that the parts employed form two separate concentric chambers, 60 each having slotted burner ports through which the gas mixture flows to the outside of the burner chambers where it may be burned and consumed.

Referring further to Figure 2, a lighter jet piece 44a is provided which is screwed or other- 70 75

wise fastened directly into the bottom of the inner chamber 28 of the burner head 25. Said lighter jet piece 44a has a central burner passage 45 which communicates with a horizontal passage 46, the one end of said passage 46 opening toward the central hole 47 of the burner head 25 and other end of said passage 46 opening in the opposite direction and toward a tube piece 48 which in this form of this invention is formed as 10 a portion of the burner head 25. Said lighter piece jet 44a has a slot 50 extending the entire length of the horizontal passage 46 as shown.

As to the operation of this invention, a gas valve is employed attached to a gas source of supply and 15 this gas valve is not shown in this drawing as it is now commonly known and used. This valve has nozzles extending into the nozzle openings 14 and 15 in the burner casting 10. Gas may therefore be supplied by means of this gas valve into either 20 or both of said mixing tubes 11 or 12 and such gas passes through the passages described and into the burner chambers 28 and 29 passing through the corresponding slotted ports 39 and 42 from which it burns in the usual manner. Gaseous 25 fuel flowing from the chamber 29 into the slots 42 flows both upwardly along the inner cylindrical surface of the outer wall 31 and diagonally outward along the under surface of the burner head center 36. As a consequence of this flow in both 30 an upward and diagonal direction, the gas on issuing from the burner port 42, takes a direction midway between the direction of said two surfaces along which the gas flows, and as a consequence the burning gas from this port 42 takes a 35 more upward direction against the vessel than in other burners of similar type. This in turn causes the burner of this invention to have a higher efficiency since the flame is burning nearer to the center of the vessel and consequently has a further travel against the vessel before it escapes into 40 the atmosphere. At the same time this invention provides a burner of relatively larger diameter and consequently a burner having a more desirable wide-spread uniform heat on low flame than 45 in previous burners having a corresponding flame action on full flame adjustment.

It is obvious why the construction I have shown and the burner I have described provides a construction in which a greater area is possible 50 in the corrugations making the burner ports. In the commonly used burner of the corrugated port style, the depth of the corrugation is limited by the practical depth that can be used for the width of a burner port. Too great a width of a burner 55 port causes a back flash of the burner and consequently such depth is definitely limited. In the burner of this invention the burner port corrugation extends directly down into the burner chamber which chamber may be as large as necessary, and consequently there is no limit to the 60 depth and consequently the area and cooling effect of the burner port corrugations. Other burners of this general style have the corrugations extending inwardly and with such inward 65 extension of the corrugation they are definitely limited in length since at a certain distance the ports will run together.

The burner of my invention may also be constructed with burner ports of a depth running 70 towards the center of the burner only about approximately equal to their width. The sufficiently large cooling area is then obtained by extending the corrugations a greater distance downward into the burner chamber, the possibilities of such construction being obvious from the description.

In this application I have not described the function and operation of the lighter jet 44a or the lighter tube 49 in view of the fact that it is fully disclosed in my co-pending application, Serial No. 709,449, filed February 2, 1934, in which a 5 complete description is given of both the parts and the operation.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A gas range burner having two mixing tubes, said mixing tubes leading to a burner means having two separate chambers therein, each of said tubes connecting to one of said chambers, one of said chambers surrounding a central hole in said burner means, the other of said chambers surrounding the first mentioned chamber, said burner means having a common wall separating said two chambers, said burner 20 having a removable top substantially engaging said common wall separating said two chambers, said top engaging said burner means in addition to the outside of said burner means and at said hole, and of said three points of a substantial 25 engagement of said burner top with said burner means, the points of engagement around said central hole being at the lowest level and the point of engagement around the outer diameter of said burner being at the highest level of all 30 three points of engagement.

2. A gas range burner having a mixing tube casting having two mixing tubes, said casting having a seating surface means in its upper side and having two openings in said seating surface 40 means, one of said mixing tubes connecting with one of said openings and the other tube to the other of said openings, a burner head having two annular substantially concentric chambers therein separated by a wall common to both of said 45 chambers, a seating surface means on the bottom of said burner head having two openings therein, said openings extending over portions only of the circumferential lengths of said chambers, one of said openings connecting to one of said 50 chambers and the other opening to the other of said chambers, each of said chambers having burner port means leading therefrom, the said mixing tube casting and said burner head being fastened together at their respective seating surfaces, the openings in the seating surface of the casting at least partially registering with the openings in the seating surface of the burner head, said burner head having a central hole 55 therethrough, one of said openings in the seating surface of said burner head being nearer said hole than the other of said openings.

3. A double gas range burner having a burner head with a burner head body part and a burner head center part, said body and said center parts 65 forming the closing means of two concentric annular chambers, said center and said body parts each having three extending concentric substantially cylindrical surfaces, each of the cylindrical surfaces on one of said parts extending within 70 the axial length of a cylindrical surface on the other part whereby said chambers are enclosed and separated from one another, said burner head center having ports leading from said chambers, the burner head body serving to par- 75

tially define the effective area of certain of said ports when the body part and center part are in assembled relation, and said two parts each having a seat, the engagement of said two seats limiting the extent to which part of the cylindrical surfaces extend within the other said cylindrical surfaces.

4. A gas range burner having a burner head comprising a burner head body part and a burner head center part, said body and said center parts forming the closing means of an annular chamber, said center and said body parts each having two extending concentric substantially cylindrical surfaces, each of the cylindrical surfaces on one of said parts extending within the axial length of a cylindrical surface on the other part whereby said chamber is enclosed, the outer extending cylindrical surface on one of said parts having grooves which coact with the outer extending cylindrical surface on the other of said parts to form an outer series of burner ports, the outer cylindrical surface on said first mentioned part extending throughout the outer portion of said part, and said two parts each having a seat, the engagement of said two seats limiting the extent to which the cylindrical surfaces of one part extend within the axial length of the cylindrical surfaces on the other part, all of said burner ports opening from said chamber to the outer atmosphere with said seats in engagement, said seats having a smaller diameter than the cylindrical surfaces which coact to form said series of burner ports.

5. A domestic range gas burner comprising a base member having a plurality of passages therein, and a burner head therefor comprising a body portion mounted on said base member having an outer wall, an inner wall and an intermediate wall, said inner and intermediate walls being in spaced relation and concentric with each other and in spaced relation and concentric with said outer wall and in stepped relation with each other with respect to height, and

a burner head center in threaded engagement with said burner head body, said burner head center having a plurality of upwardly inclined grooves on its outer periphery adjacent its upper edge and having a plurality of concentric downwardly extending surfaces on its under side adapted to coact with said outer and intermediate walls to form concentric chambers in said burner head, the inner surface of the outer wall of said body member cooperating with the grooves to form burner outer ports communicating with the outer of said chambers, the burner head center having a series of ports therethrough in communication with the inner of said chambers.

6. A domestic range gas burner comprising a base member having a plurality of passages therein, and a burner head therefor having an inner surface inclined downwardly from the outer periphery toward the center, said head comprising a body portion mounted on said base member having an outer wall, an inner wall and an intermediate wall, said inner and intermediate walls being in spaced relation and concentric with each other and in spaced relation and concentric with said outer wall and in stepped relation with each other with respect to height, and a burner head center in threaded engagement with said burner head body, said burner head center having a plurality of upwardly inclined grooves on its outer periphery adjacent its upper edge but terminating short of the upper edge thereof and having a plurality of concentric downwardly extending surfaces on its under side adapted to coact with said outer and intermediate walls to form concentric chambers in said burner head, the inner surface of the outer wall of said body member cooperating with the grooves to form burner outer ports communicating with the outer of said chambers, the burner head center having a series of ports therethrough in communication with the inner of said chambers.

PHILIP S. HARPER.
